UNITED STATES PATENT OFFICE.

ROBERT WILLIAM PAGE, OF EL PASO, TEXAS.

DESIGN FOR A TOY BALLOON.

Application filed November 11, 1922. Serial No. 4,259. Term of patent 7 years.

To all whom it may concern:

Be it known that I, ROBERT W. PAGE, a citizen of the United States, residing at El Paso, in the county of El Paso and State of Texas, have invented a new, original and ornamental Design for Balloons, of which the following is a specification, reference being had to the accompanying drawing, forming part thereof.

The figure is a plan view of a toy balloon showing my new design.

I claim:

The ornamental design for a toy balloon, as shown.

ROBERT WILLIAM PAGE.
